KEY PULLER

Vladimir N. Labounsky, New York, N. Y.

Application February 12, 1947, Serial No. 728,051

4 Claims. (Cl. 29—250)

1

My invention relates to an improved clamp, and in particular to a clamp for removing keys, such as those employed to lock a gear, wheel, or the like upon a shaft.

Those whose duty it is to maintain heavy rotating machinery are fully aware of the difficulties of removing keys such as those employed to lock gears, wheels, and other rotating parts to shafts. Frequently, in the process of removing a key, the projecting end of the key either breaks off or becomes so damaged as to make removal by means of pulling extremely difficult if not impossible.

It is, accordingly, an object of my invention to provide an improved clamp which will be particularly useful in the removal of keys.

Another object is to provide an improved key-pulling device which will be adaptable to a variety of key sizes and types and to a variety of types of installations, such as gears, wheels, and other rotating parts of different configurations.

It is still a further object to provide a key-pulling device which may meet the above objections even for relatively heavy machinery and at the same time be simple, readily portable, and easy to operate.

Other objects and various further features of the invention will be pointed out or will occur to those skilled in the art from a reading of the following specification in conjunction with the accompanying drawings. In said drawings:

Fig. 1 is a perspective view of a clamping device incorporating features of the invention;

Fig. 2 is a partially sectionalized side view of the clamp of Fig. 1; and

Fig. 3 is a right-end elevation of the clamp of Fig. 1.

Broadly speaking, my invention contemplates a clamp in which a first means is provided for adjustably closing jaws, say upon a key to be removed, and in which second adjustable means exert substantially greater forces to increase the strength of the bite of the jaws. Jacking means are provided for exerting jacking forces against the gear wheel or the like from which the key is to be removed. In the specific form to be described, the jacking means includes three jacking screws providing tripod support for the application of jacking forces. In order that the exertion of jacking forces will not harm the gear or wheel from which the key is to be removed, the jacking screws are formed with self-aligning foot portions of substantial area.

Referring to the drawings, my invention is shown in application to a clamp including a

frame member 5 having a longitudinally extending slot 6 therein. A pair of clamping jaw members 7—8 is pivotally supported by the frame member 5; these jaw members are partially received in the slot 6. Each of the jaw members includes a biting portion 9—10, which may be provided with serrations or teeth for clamping upon a key 11 to be removed. The biting serrations or teeth are preferably upwardly directed (in the sense and as shown in the drawings). The biting portions 9—10 preferably project but a relatively little distance beyond one side of the slot 6. To the other side of the slot 6 the jaw members 7—8 project a relatively greater distance to provide jack arms for the accommodation, at or near the extremities 12—13, of means for spreading these extremities apart. In the form shown, the spreading means includes a screw member 14 threadedly receivable in one of the jaw members 8 and projecting into abutment with the other jaw member 7. For better alignment of the screw 14, its end is rounded to fit within a concave portion 15 in the jaw end 12.

In accordance with a feature of the invention, the separation between points of pivotal support for the jaw members 7—8 is adjustable. This function may be accomplished by journaling one jaw member 7 in the frame member 5, as by means of a pin 16, and by adjustably positioning the other jaw member 8. In the form shown, the jaw member 8 may rock about the curved end of a slide member 17, slidably in longitudinally extending ways on the frame member 5; and the back of the jaw member 8 may be cut away, as at 18, with a concave recess to receive the curved end of the slide 17. The slide 17 may be adjustably positioned by a longitudinally extending screw threaded in one end of the frame member 5, and spring means 20 may serve constantly to urge the jaw member 8 toward the adjustable positioning means 17—19. In the form shown, the ways for the slide member 17 are provided by longitudinal slots 21 formed in the frame member 5.

As indicated above, I also provide means for jacking my clamp as a whole once the jaws 9—10 have been set upon a key or the like. The jacking means may provide tripod support, as by means of a first transversely extending screw 22 threaded in the end of the frame member 5 opposite the jaw-positioning screw 19, and by means of two further screws 23—24 straddling the frame 5. In the form shown, the jack screws 23—24 are threaded in bosses 25—26 forming parts of a yoke 27, pivotally attached (as by the

pin 28) to the jaw member 8, and extending in clearance relation with and around the frame 5. The lower ends of the jack screws 22-23-24 may be provided with self-aligning feet 29 including ball-and-socket joints 30 and having enlarged footing areas for better distribution of jacking forces.

In operation, I recommend that the above-described clamp be used in the following manner in order to remove a key from its locking engagement with a shaft or the like and with a gear, wheel, or the like. The jaws 9-10 are spread sufficiently, by backing the adjustable means 19, to span a key 11, with the frame 5 transverse to the sliding axis of the key 11 and with the jack arms 12-13 projecting more or less along this axis. The screw 19 is then tightened as much as possible, as by applying a wrench to the outwardly projecting end thereof. The jaw-spreading screw 14 may next be tightened, again as much as manually possible—although in many cases a light setting of the screw 14 will suffice. The clamp is then substantially set, and it remains to apply jacking forces by adjustment of the jack screws 22-23-24.

It will be understood that, no matter how irregular the surfaces against the screws 22-23-24 must work may be, the feet 29 may adapt themselves readily so as to provide a properly aligned jacking axis. It will also be understood that as jacking forces begin to be applied, the upwardly-directed (in the sense of the drawings) teeth of the jaws 9-10 may dig into the key 11 to permit greater tightening of the screw 14, with an increase in effectiveness of the grip of the jaws 9-10.

It will be appreciated that I have described a relatively simple means for applying tremendous forces first to grip and then to jacking. Even in application to keys employed in heavy machinery, the clamp mechanism may be made readily portable. The device is easy to operate and adaptable to a wide variety of types and sizes of keys or the like.

Although I have described my invention in detail for the preferred form shown, it will be understood that modifications may be made within the scope of the invention as defined in the claims which follow.

I claim:

1. In a clamp, a frame member having a longitudinally extending slot, a pair of jaw members to be received in said slot, each of said jaw members including a biting portion and a jack arm relatively remote from said biting portion, pivotal-support means for supporting said jaw members in said slot with the biting portions relatively close to said supporting means, adjustable means for spreading said jack arms, whereby substantial mechanical advantage may be obtained in the gripping of said biting portions, a yoke member pivotally supported from one of said jaw members for movement about an axis substantially parallel with the axis of the pivotal-support means and encompassing a part of said frame member, said yoke member including jacking means for exerting jacking forces generally normal to the bite of said jaw members.

2. A clamp according to claim 1, in which further jacking means are provided in the end of said frame opposite from the jaw to which said first-mentioned jacking means are applied, whereby the net jacking thrust provided by all said jacking means may be aligned generally normal to the bite of said jaws.

3. In a clamp having a pair of coacting jaw members, each jaw member being provided with a biting portion, a frame member having a longitudinally extending slot, one of said jaw members being receivable in said slot for rockable and slide movement, the biting portion of said jaw projecting from one side of said slot and a jacking portion projecting from the other side of said slot, pivotal support means on said frame member for said movable jaw member, adjustable positioning means for the pivotal support means longitudinally movable on said frame member, and a pair of spaced jacking means to exert force in a direction generally normal to the biting portions, one of said jacking means being pivotally supported on said one jaw member.

4. In a clamp having a pair of coacting jaw members, each jaw member being provided with a biting portion, a frame member having a longitudinally extending slot, one of said jaw members being receivable in said slot for rockable and slide movement, the biting portion of said jaw projecting from one side of said slot and a jacking portion projecting from the other side of said slot, a second slot in said frame member disposed generally at a right angle to said first slot, a slide member in said second slot and engageable with said movable jaw member to provide pivotal support therefor, adjustable means carried on said frame member behind said slide member and in engagement with it for adjustably longitudinally positioning said movable jaw member, and a pair of spaced jacking means to exert force in a direction generally normal to the biting portions, one of said jacking means being pivotally supported on said one jaw member.

VLADIMIR N. LABOUNSKY.
